(57) CLAIM

The ornamental design for a nail manicure machine, as shown and described.

DESCRIPTION

FIG. 1 is a front perspective view of a nail manicure machine, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an additional front, right, and top perspective view of the nail manicure machine of FIG. 1 wherein the lid is closed; and,

FIG. 10 is an enlarged detail view of area 10 in FIG. 1.

The dash-dash broken lines in the drawings illustrate portions of the nail manicure machine that form no part of the claimed design. The dash-dot-dash broken lines illustrate the bounds of the area in FIG. 1 that corresponds to the enlarged view in FIG. 10 and form no part of the claimed design.

1 Claim, 10 Drawing Sheets
